PATENTED SEPT. 18, 1906.

W. I. WENTWORTH.

MACHINE FOR MANUFACTURING BOOT AND SHOE HEELS.

APPLICATION FILED DEC. 8, 1903.

UNITED STATES PATENT OFFICE.

WINSLOW I. WENTWORTH, OF BROCKTON, MASSACHUSETTS.

MACHINE FOR MANUFACTURING BOOT AND SHOE HEELS.

No. 831,126.

Specification of Letters Patent.

Patented Sept. 18, 1906.

Application filed December 8, 1903. Serial No. 184,814.

To all whom it may concern:

Be it known that I, WINSLOW I. WENTWORTH, a citizen of the United States, residing at Brockton, in the county of Plymouth and State of Massachusetts, have invented new and useful Improvements in Machines for Manufacturing Boot and Shoe Heels, of which the following is a specification.

My invention relates to machines for manufacturing or building up boot and shoe heels, and has for its object to provide a machine for automatically forming and shaping such heels, to provide means for so automatically forming the heels as to impart thereto a dished conformation or seat to conform to the heel structure of the boot or shoe without the necessity of the utilization of rands, and, third, to provide in an automatic heel-building machine means by which the height of the heel may be varied.

My invention has also for its object to improve the construction and mode of operation of machines for building boot and shoe heels.

To the ends stated the invention consists in a heel-building machine having the novel combination and arrangement and mode of operation of parts as hereinafter described and claimed.

In the accompanying drawings, illustrating the best-known and preferred embodiment of my invention, Figure 1 is a view, partly in elevation and partly in section. Fig. 2 is a front elevation. Fig. 3 is a detail view showing the movable preliminary heel-form, which is adapted to receive the several lifts composing the heel, and its coöperative relation to the mold-chamber through which the material is passed and from which it is expressed, as hereinafter described. Fig. 4 is a sectional view illustrating the heel-mold, the heel-seat die, and adjacent mechanism. Fig. 5 is a plan view illustrating the seat-forming die, the roller for shaping the vertical surface of the heels, and correlated elements. Fig. 6 is a plan view illustrating the means for adjusting said roller to coöperate with different-sized heels. Fig. 7 is a detail of the track on which said surface-shaping

roller carriage travels, showing also the ratchet with which said carriage is intermittently engaged and by which it is caused to travel on said track. Fig. 8 is a detail view of the end of the arm which coöperates with the lock and connects and disconnects the

heel-surface-roller carriage with the means for driving the same. Fig. 9 is a perspective view of the heel-seat die.

In the said drawings the reference-numeral 1 designates a framework or support of any suitable character, connected to which is a table 2. Arranged to slide on this table is a preliminary heel-form 3, in which heel-lifts sufficient to construct a heel of the desired height are arranged by a workman and in which they are carried to the mold 4, herein-after described, said lifts being supplied with a suitable cement whereby they are secured together.

The numeral 4 designates a mold chamber or passage through the table 2 and conforming in outline to that of the heel-lifts of which the heel is to be constructed. As shown, this mold-chamber is formed in a suitable metallic casting 5, set into the table 2 in any desired manner. It is designed that the workman shall place in the preliminary form 3 a number of heel-lifts sufficient to form, in finality, a complete heel and shall then slide the preliminary form into coincidence with the mold 4.

The numeral 6 designates a plunger fitted to move in a guide-standard 7 and provided with an adjustable die 8. The plunger is operated conveniently by a rock-arm 9, actuated through the medium of an eccentric ring 10, connected thereto, which ring is engaged by an eccentric 11, carried by a counter-shaft 12 of the machine, which counter-shaft is driven by a gear 13, meshing with a gear 14, mounted on an intermediate shaft 15, driven by a gear 16, that meshes with a gear 17 on the main driving-shaft 18. Beneath the mold 4 is arranged a support 19, which offers resistance to the plunger 6 and die 8, and therefore takes an active part in the formation of the heel-stock, and by which, together with the mold 4, the stock is held while being shaped, as hereinafter set forth. This support 19 serves, furthermore, as a heel-seat die, the formation of which (shown enlarged in Fig. 9) operates to dish the appropriate surface of the heel to form a heel-seat conforming to the shape of the heel portion of the boot or shoe it is to receive. By imparting this dished form or heel-seat formation to the heel the necessity of utilizing the commonly-known rand is dispensed with.

It is designed according to my invention that several batches of heel-lifts, each batch

sufficient to form a complete heel, shall be introduced into the mold and expressed therefrom progressively by the plunger, which has a throw adjustably variable by adjustment of the die 8 equal to the predetermined height of the heel to be manufactured. It will therefore be seen that in the progress of the incomplete heel through the mold it receives a plurality of compressions between 5 the die on the plunger and the heel-seat die, whereby the several lifts thereof are well compacted together, and that portion of the heel which is lowermost in its progress through the mold receives the dished or heel-seat formation imparted by the heel-seat die, 10 as hereinbefore mentioned.

In order to permit of variation in the height of heels built up or manufactured by the machine, the heel-seat die is adjustable with relation to the mold, a suitable means for accomplishing this being as follows: The heel-seat die is provided with a spindle 20, that passes down through the hereinafter-described roller-carriage and enters a sleeve 21, 15 suitably formed or attached to the frame 1. This spindle is provided with a key 22, that engages an appropriate slot in the sleeve to prevent rotation of the spindle. Rotation thereof may, however, be prevented in any 20 other suitable manner. The lower end of the spindle is suitably threaded, as shown at 23, and a nut 24 is mounted in the sleeve and engages the screw-thread of the spindle, whereby upon rotation of said nut the heel-seat die 25 is adjusted to and from the mold to permit of the building up or construction of heels of different heights.

The numeral 25 indicates a rotatable carriage, which, as shown in the accompanying drawings, is mounted to rotate about the spindle of the heel-seat die. Pivotedly carried by this carriage is a roller 26, that operates against the vertical face or edge of the heel and is suitably shaped to impart the desired curvature or contour to said edge of the heel.

Because of the fact that the contour of the heels is not circular, but approximately elliptical; in shape, it is desirable that the heel-surface roller 26 shall be capable of a variable path of movement to conform to the peculiarity of the contour of the heel, and to this end it is pivoted to the carriage, as at 27, as before mentioned, and is operatively engaged by a controlling device consisting of a roller 28, traveling upon a stationary track 29, which track is provided with elevations 30, coincident with the minor diameter of the heel-seat die and the heel to be manufactured, whereby in the rotation of the carriage 25 the said controlling-roller will ride upon said elevations and tilt the said heel-surface roller 26 inward toward the heel, and when riding upon the lower portion of the 65 track said heel-surface roller will be permit-

ted to move outward. The heel-surface roller is thus caused to move in a path conforming to the shape of the heel and adequately press and give shape to the vertical edge or surface thereof.

It is designed that the rotation of the carriage 25 shall be caused intermittently and after the plunger has expressed from the mold onto the heel-seat die a sufficient quantity of material to construct a heel, and to 70 this end the said carriage is intermittently locked to a ratchet-wheel 31, formed rigid with a hub 32, having a pinion 33 in mesh with a pinion 34 on one end of a shaft 35, the other end of which is provided with a pinion 36, meshing with a gear 37 on the intermediate shaft 15, whereby said ratchet is constantly rotated. To connect the carriage 25 with said ratchet, so that it will be thereby caused to rotate, said carriage is provided with a locking-dog 38, one arm of which is adapted to engage the teeth of the ratchet and the other arm of which is adapted at each rotation of said carriage to enter the forked end of a pivoted arm 39, the other end of 80 which is engaged by a cam 40 on the counter-shaft 12, which cam is so timed in relation to the plunger-operating mechanism that after a heel-stock has been expressed from the mold onto the heel-seat die the forked end of 90 said arm will be free to respond to the impulse of a spring 41 and cause the upper member of the forked end of said arm 39 to engage the correlated arm of the locking-dog 38 and throw said dog into engagement with 100 the ratchet-wheel 31, whereby the carriage is caused to rotate with said wheel. During a complete rotation of the carriage the dog is held in engagement with the ratchet-wheel by the inner edge 42 of the track 29. At the 105 end of a complete rotation of the carriage, during which the heel-surface roller properly acts on the vertical edge of the heel, as above described, the arm of the locking-dog again enters the forked end of the arm and riding 110 upon the inclined edge of the lower member of said fork causes the acting end of the locking-dog to be disengaged from the ratchet-wheel, a sufficient clearance-space 43 at this point being provided for that purpose. Upon 115 disengagement of the locking device with the ratchet-wheel the rotation of the carriage ceases. It will be observed from this description that the said carriage is caused intermittently to partake of a complete rotation, and this rotation occurs after sufficient heel-stock has been expressed from the mold.

A reciprocating knife 44 is provided, said knife being connected by a link 45 with the eccentric that operates the plunger-operating 125 arm, as best shown in Fig. 1 of the drawings, the operation of which is so timed with relation to the other mechanism of the machine that after the vertical edge of the heel has been shaped by the roller 26, as described, 130

the knife will be projected across the discharge-mouth of the mold and sever the completed heel from the stock.

The roller 26 for operating against the vertical face of the heel is mounted on an adjustable yoke 46, Figs. 5 and 6, which is adjustable in the carriage 25 by means of a screw 47, whereby said roller may be moved to or from the center of the heel-seat die 19, and thus caused to travel in paths more or less removed from the center of said die 19 to accommodate heels of different widths and lengths.

As will be observed in the following clauses of claim, I claim my invention as embodied in the machine as an entirety and also the several novel subcombinations of parts. I do not restrict my invention to the details of construction and arrangement illustrated and described, except as the same may be set forth in some of the following clauses of claim and then only for the purpose of those particular clauses.

Having thus described my invention, what I claim is—

1. In a machine for manufacturing boot and shoe heels, the combination with heel-stock-forming mechanism, of means for shaping the vertical surface of a heel while held by the forming mechanism, and means for separating a heel from the stock.

2. In a machine for manufacturing boot and shoe heels; the combination with heel-stock-forming mechanism, of a device for shaping the vertical surface of a heel while held by the forming mechanism, means for revolving said device about the heel-stock, and means for separating a heel from the stock.

3. In a machine for manufacturing boot and shoe heels, the combination with heel-stock-forming mechanism, of a device for shaping the vertical surface of a heel while held by the forming mechanism and means acting upon said device to adapt it to the contour of such surface.

4. In a machine for manufacturing boot and shoe heels, the combination with a heel-stock mold, of a die in co-operative relation

thereto, means for pressing the stock upon said die and means for separating a heel from the stock.

5. In a machine for manufacturing boot and shoe heels, the combination with heel-stock-forming mechanism, of a device for shaping the vertical surface of a heel while held by the forming mechanism, means for moving said device about the stock, and means for periodically connecting and disconnecting said moving means.

6. In a machine for manufacturing heels for boots and shoes, the combination of a mold, a heel-lift carrier in which the lifts are carried to the mold, a heel-seat die, a plunger for forcing the heel-lifts through the mold onto the die, and means for separating a heel from the stock.

7. In a machine for manufacturing heels for boots and shoes, the combination of a mold, a heel-lift carrier in which the lifts are carried to the mold, a heel-seat die, a plunger for forcing the heel-lifts through the mold onto the die, means for shaping the vertical face of the heel-stock, and means for separating shaped heels from the stock.

8. In a machine for manufacturing heels for boots and shoes, in combination with heel-stock-forming mechanism, a heel-seat die co-operatively arranged in relation thereto, means for shaping the vertical face of the heel-stock, means for separating shaped heels therefrom, and means for varying the height of the heels.

9. In a machine for manufacturing boot and shoe heels, the combination with a heel-stock mold, of a heel-seat die in co-operative relation thereto, means for pressing the stock upon said die, means for shaping the vertical surface of a heel, and means for separating a heel from the stock.

In testimony whereof I have hereunto set my hand in presence of two subscribing witnesses.

WINSLOW I. WENTWORTH.
